UNITED STATES PATENT OFFICE.

ALBION P. AIKEN, OF PORT PERRY, PENNSYLVANIA.

LIFTING-JACK.

SPECIFICATION forming part of Letters Patent No. 509,565, dated November 28, 1893.

Application filed January 31, 1893. Serial No. 460,449. (No model.)

To all whom it may concern:

Be it known that I, ALBION P. AIKEN, a citizen of the United States, residing at Port Perry, in the county of Allegheny and State 5 of Pennsylvania, have invented certain new and useful Improvements in Lifting-Jacks; and I do hereby declare the following to be a full, clear, and exact description of the invention, such as will enable others skilled in the 10 art to which it pertains to make and use the same, reference being had to the accompanying drawings, which form a part of this specification.

My invention relates to an improved lifting jack, and consists in a base plate, a rack bar pivoted therein, a lifting bar operating on said rack bar, and suitable means for operating the lifting bar vertically, together with certain details of construction and combination of parts as will be fully described hereinafter.

In the accompanying drawings, Figure 1, is a side elevation of my improved lifting jack, which is constructed in accordance with my 25 invention. Fig. 2 is a side elevation of the same, partly in section, and showing a modified form of the lower lifting lug. Fig. 3 is a sectional plan view taken on the line $x-x$.

To put my invention into practice I provide 30 a box shaped base plate 27 and pivot therein by means of short pins 26 a rack bar 6. This rack bar 6 is provided at its base with integral lugs through which the pins 26 are passed, and with a lug 25 at the opposite side through 35 which a short movable shaft 28 operates to hold the said rack bar rigid in a vertical position. This shaft 28, is fitted loosely in an integral lug 30, and one of the side walls of the base plate, and limited in its movement 40 by a cotter pin 28^a. This rack bar is provided with racks 7, and 8 arranged at opposite sides to each other, and two grooves 5 extending in the direction of the length of the said bar for the purpose of connecting the lifting bar 1 thereto. Loosely connected to this rack 45 bar 6 in a manner that the same may be free to move vertically, is a lifting bar 1 having an integral portion 2 which overlaps the rack bar 6, and engages with the grooves 5, and 50 thereby confining the two together. Formed integral with this overlapping portion 2, is a bearing 3 in which is pivoted by means of

pins 17 a lever 18 having a socket 16. Pivoted within the lever 18 is a stout pawl 14 which engages with one of the racks 8. This 55 pawl is formed with a handle 19 which also acts as a counterweight to keep the said pawl engaged with the rack. Operating within a recess 10 formed at the inner side of the lifting bar 1 is a pawl 9 pivoted at the top by 60 means of a pin 11, and adapted to engage with the rack 7 of the rack-bar 6. Hinged to the lower end of this pawl 9 is a link 13 which serves as a means for disengaging the said pawl from the rack 7, and also as a counterweight to keep the pawl engaged with the 65 said rack. Formed on the lower edges of this link 13 are downwardly extending portions 22, which when the pawl 9 and lifting bar 1 are moving upward passes over an inclined 70 surface, thereby moving the pawl out of the rack 7, to engage with the next tooth above.

In operation, the socket 16 is given a vertical movement by means of a suitable lever, and on the downward stroke engages the 75 pawl 14, with the rack 8, which pawl acting as a fulcrum, elevates the lifting bar 1, and engages its pawl 9 with the next tooth above. This vertical movement is continued, and the lifting bar 1 with its lift 4 elevated to the 80 desired height. To lower the lifting bar step by step, the lever is pressed slightly down to remove the weight from the pawl 9, and the link 13, operated to remove the pawl 9 from the rack 7 and enter the same in the next 85 tooth below. The pawl 14 pivoted to the lever is now disengaged from its rack by means of the handle 19 and lowered one tooth, and the same operation as before described continued until the lifting bar has been lowered 90 the desired distance. To lower the rack bar 1 rapidly it is only necessary to move the link 13 upward and engage the same with the under side of the handle 19 as shown in dotted lines at Fig. 2 on the drawings, which 95 releases the two pawls and permits the lifting bar to descend. By pivoting the rack bar in the manner described, the same may occupy an inclined position, and the base 27, rest firmly on the ground in a horizontal position. If it is desired to hold the rack-bar 100 in a vertical position, the rod 28 is passed through the lug 25, and the said rack-bar held rigid at right angles to the base.

At Fig. 2 on the drawings I have shown a pivoted lift 4' at the base of the lifting bar 1, having rearwardly extending bearings in which a friction roller 24 is arranged, adapted to engage with the side of the rack-bar to reduce the friction on the grooves 5.

The pawl 9, may, if desired, be formed with a hook, and the position of the same inverted, and operated by the link 13, without altering 10 or departing from the invention.

Having thus described my invention, what I claim, and desire to secure by Letters Patent, is—

1. The combination, with the vertically disposed rack-bar,—of a vertically slideable lifting bar loosely connected to said rack-bar,—a pawl pivoted in a recess in the lifting bar and adapted to engage adjacent teeth of the rack-bar,—and means for actuating the lifting bar.

2. The combination, with a vertically disposed rack-bar,—of a vertically slideable lifting bar loosely connected to the rack-bar,—a pawl pivoted on the lifting bar and adapted to engage adjacent teeth of the rack-bar,—a detent-link for throwing the said pawl out of engagement with said teeth,—and means for actuating said lifting bar.

3. A lifting-jack comprising a base-plate,—

a double faced rack-bar pivotally connected thereto,—a lifting bar slidably connected to the rack-bar,—a pawl pivoted to the lifting bar and designed to engage adjacent teeth of the rack-bar,—a detent-link connected to said pawl and designed to enable its disengagement,—a power-applying lever controlling the movement of the lifting bar,—a pawl attached to said power-lever and adapted to engage the adjacent teeth on the opposite side of the rack-bar,—and a suitable loose connection between the lifting and rack bars.

4. The combination with a double faced rack-bar,—of a lifting bar slidably connected thereto,—a pawl pivoted to said lifting bar and capable of engaging the adjacent teeth of the rack-bar,—a power-applying lever controlling the lifting bar,—and a gravity-pawl attached to the power-lever and capable of engaging the adjacent teeth on the opposite face of the rack-bar.

In testimony that I claim the foregoing I hereunto affix my signature this 16th day of January, A. D. 1893.

ALBION P. AIKEN. [L. S.]

In presence of—

H. J. LEVIS,
JAS. J. McAFFEE.
